CAN OPENER

Gustaf L. Reenstierna, Union City, N. J., assignor
of one-half to Remo Aiazzone, Union City,
N. J.

Application May 11, 1940, Serial No. 334,484

12 Claims. (Cl. 30—17)

My invention relates to can openers for piercing and cutting the top of sheet metal cans and particularly to cylindrical tin cans for domestic use and has among its purposes and objects to provide:

A can opener which cuts and forms a pouring lip.

A sanitary can opener.

A can opener which cuts the top of a metal can and bends the cut portion to provide an outwardly extending lip for pouring.

A convenient can opener requiring little manual effort.

A can opener which permits the contents of the can to be completely emptied without dripping.

A can opener which holds the can while being opened.

A safe can opener which cannot slip and injure the user.

A can opener which partially cuts out a part of the top without bending the partly cut portion into the can.

I accomplish these and other objects by the construction herein described and illustrated in the accompanying drawing forming a part hereof in which:

Fig. 1 is a plan view.

Fig. 2 is a plan of the swing joint.

Fig. 3 is a sectional elevation along the longitudinal centerline.

Fig. 4 is an elevation of the end of the cutting lever.

Fig. 5 is a bottom view.

Fig. 6 is a perspective view showing the application of my device in cutting the can.

Fig. 7 is a perspective view showing the application of my device in bending the pouring lip.

Similar reference characters refer to similar parts throughout the several views of the drawing and in the specification to follow.

Can openers are so well known to the housewife that a statement of their disadvantages, danger, and shortcomings need not here be enumerated and the advantages of my can opener will at once be apparent to anyone when its construction and operation are understood. My device holds the can by being secured to it. The cutter is secured to a lever so that little effort is required to cut the tin top of the can. The lip is not forced into the can when it is cut but is bent outwardly to provide a pouring lip and because the lip is bent close to the rim of the can all of the contents may be emptied from the can and most of the solid food as well as liquid is easily poured out. Beans, spaghetti, soup and many fruits and

canned vegetables may be poured out without removing the top end of the can. For liquids and pasty or gruel-like contents, the contents may be poured out without dripping or a part of the contents withheld as is the case of such material in a can when opened by a can opener which forces the lip into the can. The dirt on the top of the can is not mixed with the contents of the can when it is opened; thus the contents of the can opened by my device is kept clean and sanitary.

I have herein illustrated and described in detail one of the constructions embodying the underlying principles of my invention. I do not wish to be confined to these details as they are disclosed herein to illustrate rather than limit the scope of my invention and to those skilled in the art to which it pertains it is expected that numerous modifications will be apparent in adapting my can opener to the many uses for which it is adapted.

I have provided a clamp member 1 preferably provided at one end with a downwardly depending lug 2 bent at right angles from the shank 3. The lug 2 is provided with the boss 4 extended from the metal of said lug and tapped to receive the clamp screw 5 which is provided at one end with the wing head 6 and at the other end with the loose clamp plate 7 which receives the end of the clamp screw 5 permitting it to freely revolve therein. The clamp plate 7 engages the rim 8 of the can 9 and cooperates with the downwardly depending ears 10 and 11 which are bent downwardly from the metal of the spider 12 at the opposite end of the clamp member 1. The top rim of the can is thus held between the plate 7 and ears 10 and 11 by tightening the screw 5 in the lug 2. The spider is preferably formed integral with the shank 3 and is cut out at 13 within its margin 14 to permit the travel of the cutter 15.

The spider at its center terminates into the turn table 16 which thereby forms the extreme opposite end of the member 1 from the clamp lug 2. The turn table is apertured to receive the pin 17 on which the swing joint 18 is swung.

The swing joint is preferably disc shaped and is provided with diametrically opposed upturned ears 19 and 20 which receive the pin 21 on which the bearings 22 and 23 of the lever 24 is vertically swingingly mounted. The bearings 22 and 23 may be formed integral with the lever 24 and bent around and back upon the top surface of said lever. The bearings 22 and 23 are spaced apart thereby providing room between them for

the torsional spring 25 around said pin 21 causing the lever 24 to be normally held in its lowered position against the detent 26 which engages the hole or depression 27 in the center of the shank and spider and which thus holds the lever in its center position when not in use.

The lever 24 is prevented from being raised more than is necessary for its operation by the stops 28 and 29 formed on the ears 19 and 20. The lever is prevented from swinging horizontally more than is necessary by the center upturned stop lug 30 which contacts the ears 19 and 20 at each end of its swing thereby preventing the cutter from striking the cut out marginal edges of the spider.

The cutter 15 is preferably secured to the under surface of and swung by the lever 24 and is so shaped and disposed downwardly from the lever 24 as to pierce the top 31 of the can 9 at or near the edge of the rim 8 as to cause the lip cut by it to turn upwardly along its edge 32. The cutter is beveled so that its cutting edge is on the side toward the pin 17 around which it moves which causes the edge of the top of the can to be bent slightly downward or opposite to the upward bend along the edge of the lip which is caused by the pressure of said edge against the flat face of the cutter between its cutting edges. This pressure is caused by the difference between the arc on which the cutter travels and the flat surface of the cutter.

The cutter is disposed also on an incline rather than perpendicular to the under surface of the lever 24 thereby providing an upward pressure to raise the marginal edge 32 of the lip 33 as may be seen in Fig. 3 of the drawing.

At the end of the lever opposite the bearings 22 and 23, I have provided a tongue 34 which preferably lies on a plane parallel to the upper surface 35 of the lever 24 and spaced sufficiently above it to receive the lip which is forced between the surface 35 and the lower surface 36 of the tongue 35 which is preferably provided with a beveled end 37 to facilitate engaging the edge of the lip. The raising of the lever 34 as may be seen in Fig. 7 causes the lip to bend to the desired position for pouring; the pressure required to bend the lip as well as the curved rim of the can cause the lip to be disked thereby assisting the flow of the contents of the can on its surface which was on the inside of the can before the lip was bent.

To guide the clamp plate 1 and to prevent it from turning, I have provided the T head 38, the neck 39 of which travels in the slot 40 in the shank 3 of the member 1.

The slope or angle of the cutter, its width and the radius on which it swings may be varied to suit the conditions and size of cans which it is desired to open. The size and shape of the parts may be also made to suit the operating conditions.

Having thus described and illustrated one of the embodiments of my invention, what I claim is new and wish to secure by Letters Patent is set forth in the appended claims.

I claim:

1. In a can opener, a clamp member and means thereon detachably securing said member to a can and a lever and cutter secured thereto, said lever swingingly mounted to said member to swing on a center outside the periphery of the top of the can to cut a lip in the top of a can.

2. In a can opener, a clamp member and means

thereon detachably securing said member to a can and a lever and cutter secured thereto, said lever swingingly mounted to said member to swing on a center outside the periphery of the top of the can to cut a lip in the top of a can and means positioned above said center hinging and permitting said lever to be raised upwardly.

3. In a can opener, a clamp member and means thereon detachably securing said member to a can and a lever and cutter secured thereto, said lever swingingly mounted to said member to swing on a center outside the periphery of the top of the can, said cutter having a beveled edge, the cutting edge of which is disposed on the face 10 away from the center of the top of the can and toward the center on which said lever swings.

4. In a can opener, a clamp member and means thereon detachably securing said member to a can and a lever and cutter secured thereto, said lever swingingly mounted to said member to swing on a center outside the periphery of the top of the can, said cutter having a beveled edge, the cutting edge of which is disposed on the face 20 toward the center on which said lever swings, said cutter having a surface, a part of which is at less radial distance than said cutting edge thereby turning the edge of the lip upwardly.

5. In a can opener, a clamp member and means thereon detachably securing said member to a can and a lever and cutter secured thereto, said lever swingingly mounted to said member, said cutter having a beveled edge, the cutting edge of 30 which is disposed on the face toward the center on which said lever swings to bend the edge of the 35 cut in the can top at a radius on which the lever swings downwardly.

6. In a can opener, a clamp member and means thereon detachably securing said member to a can and a lever and cutter secured thereto, said lever swingingly mounted to said member, said cutter having a beveled edge, the cutting edge of 40 which is disposed on the face toward the center on which said lever swings, said cutter having a surface, a part of which is at less radial distance than said cutting edge to bend the edge 45 of said lip upwardly at a radius on which said lever swings.

7. In a can opener, a member having a depending lug and clamp screw therein at one end of 50 said member and downward disposed ears near the opposite end to engage and detachably secure said member to the top of a can and means having a cutter thereon swingingly mounted in said member to cut an arc in the top of the can and a lip formed by said arc and means turning the edge of said arc upwardly when cut.

8. In a can opener, a member having a depending lug and clamp screw therein at one end of 60 said member and downward disposed ears near the opposite end to engage and detachably secure said member to the top of a can and means having a cutter thereon swingingly mounted in said member to cut an arc in the top of the can and a lip formed by said arc and means turning the edge of said arc downwardly in the 65 cut out portion of the can top and the edge upwardly of the lip.

9. In a can opener, a member having a clamp screw at one end of said member and downward disposed ears near the opposite end to engage and detachably secure said member to the top of a can, a swing joint swingingly mounted on said member and positioned outside the periphery of the can to move on a horizontal plane and a lever and cutter secured thereto said lever swingingly

mounted in said swing joint to move vertically to engage the can top and to cut an arc having its ends near the periphery of the can.

10. In a can opener, a member and means engaging and detachably securing said member to the top of a can and a lever having a cutting edge movable vertically and horizontally in relation to said member, said lever having its center of movement outside the periphery of the top of said can.

11. In a can opener, a member having a depending lug and clamp screw therein at one end of said member and downward disposed ears near the opposite end to engage and detachably secure

said member to the top of a can and a lever having a cutting edge movable vertically and horizontally in relation to said member, a detent and spring means moving said lever vertically to hold said detent in contact with said member.

12. In a can opener, a member and means engaging and detachably securing said member to the top of the can and a lever having a cutting edge movable vertically and horizontally in relation to said member, a detent and spring means moving said lever vertically to hold said detent in contact.
